YARN DELIVERY ARRANGEMENT AND METHOD

James H. Sawyer, Clemson, S.C., assignor to Deering Milliken Research Corporation, Pendleton, S.C., a corporation of Delaware

Filed Dec. 19, 1956, Ser. No. 629,305

5 Claims. (Cl. 242—128)

This invention relates to a unique method and apparatus for controlling twisted fine denier yarns, particularly fine denier synthetic yarn such as nylon etc., during overend delivery of the yarn from a package, and more particularly relates to a unique method and apparatus for controlling the yarn during this operation and while stopped, in order to prevent or minimize kinking of the yarn and to obtain a minimum of yarn tension nonuniformity during delivery irrespective of the point of delivery of the yarn from the package.

In the art of knitting apparel such as stockings, etc. from fine denier twisted synthetic yarn there are two major problems which cause considerable difficulty. One of these problems is that of tension variations in the yarn as it is pulled off from the supply package, such variations causing the apparel to be streaked in appearance and of sufficient magnitude frequently causing press-off or break-out (i.e. breakage) of the yarn; this latter defect normally resulting in complete waste of that portion of the stocking already knitted. A second difficulty is that of the formation of kinks in the yarn during the delivery of the yarn from the package and particularly during periods of stoppage of the withdrawal of the yarn from the package, stoppage of withdrawal of yarn from a particular package normally occurring several times during the process of knitting a single stocking.

It is accordingly a major object of this invention to provide a simple and effective method and apparatus for preventing or greatly minimizing tension variations, break-outs or press-offs and the formation of kinks in the yarn during delivery from a package in the knitting operation, particularly as such relates to the knitting of apparel such as stockings.

According to a preferred application of the invention, yarn is withdrawn from a substantially barrel-shaped package formed on a cone, over and about the exterior guide surface of each of a pair of annular guide members which are disposed at the small end of the cone, both of the guide surfaces being axially as well as radially spaced from each other and from the adjacent end of the yarn package formed on the cone. The yarn is pulled off in continuous engagement with the axially and radially outer annular guide surface, and intermittently contacts the axially and radially inner guide surface, such latter contact occurring as the delivery point of the yarn on the package approaches and is at the end of the package adjacent to the inner guide surface. The upper or axially outer annular guide surface is radially larger than the axially inner guide surface and the space traversed by the yarn between the two annular guide surfaces is completely free and unobstructed. This latter feature of arranging a radially and axially inner annular guide surface and a radially and axially outer guide surface in such a relation to each other and the package that the yarn path space between the two annular guide surfaces is free and unobstructed is a highly important feature of this invention since it is a major factor in contributing to the maintenance of a more uniform tension than is

2

normally obtained with similar prior art methods and apparatus, particularly such as shown in U.S. Patent No. 1,206,870 to Lipps, who teaches the requirement of a ring of plush around the middle annulas of a tapered single flange on a straight cylindrical spool. The engagement of the yarn with the pile fibers of this plush material causes high frequency tension variations which are of such magnitude as to be very undesirable, particularly when fine denier yarn is attempted to be withdrawn at desired tensions of $\frac{1}{2}$ to 2 grams or less. Also in such arrangements employing pile material, the entry and departure of the yarn in respect of the plush causes abrupt tension variations of very considerable magnitude relative to the desired tension, this being further obviously extremely undesirable.

Another important feature of the invention is the delivery of the yarn over the small end of the cone on which the package is formed, this serving when used in conjunction with the dual sized guide surfaces at the small end of the cone to additionally aid in maintaining a more uniform tension throughout the delivery of the yarn. One factor in the effectiveness of this latter feature is the fact that as the point of delivery varies from one end of the package to the other, the withdrawal over the small end of the cone and over the dual spaced apart annular guides results in a minimum of variation in the degree of yarn-to-yarn contact between the delivered yarn strand and the yarn on the package.

A further feature of the invention as practiced in accordance with the preferred application thereof lies in the disposition of the axially and radially inner guide surface at a point spaced apart from the adjacent end of the yarn package per se. One result of this feature is the prevention or minimizing of large tension variations and press-off or breakage of the yarn as the delivery point approaches and is at the adjacent end of the yarn package, which variations and breakage normally result from large change of wrap around angle on a disc or flange engaging or very close to the yarn package, from slapping of the yarn against the face of the flange, and from entrapment between the package and the flange. The space between the axially inner annular guide surface and the adjacent end of the yarn package per se should thus be sufficiently large to prevent the wrap around angle of the yarn on the small disc from becoming too large so as to cause large tension changes or press-off as the delivery point is at the end of the package adjacent the inner guide surface, and also to prevent the yarn from being thrown up against the axially inner face of the inner guide surface. It is necessary, however, that the distance between the smaller guide surface and the adjacent end of the yarn package be sufficiently small, considering the coefficients of friction of the yarn and the guide surfaces as well as the diameter of the smaller guide surface and the adjacent end of the package, that the yarn does not engage the end of the cone during delivery movement between the package and the guide member, such end being normally comparatively quite rough, and in any case such engagement would cause undesirable fluctuations of tension which in many instances would be of sufficient magnitude to cause breakage of the yarn.

In employing the two dual sized spaced apart annular guide surface members for the yarn it is important that the space between the two guide members be sufficiently great, considering the desired diameters and ratio of the diameters of the two annular guide members, that the axially inner guide member will be effective to engage the yarn as it is delivered from the package at the end adjacent the inner disc. On the other hand, during delivery of the yarn over the two guide surfaces the point of circumferential contact of the yarn with the inner

guide surface will tend to lag behind the point of contact with the axially outer guide surfaces, and it is necessary that the axial distance between the two guide surfaces be sufficiently small that the yarn will not wrap around the member employed to separate the two guide surfaces, the separator member in the preferred application of the invention being a cylinder which fits over the nose of the cone. It has been found that for most practical applications of the invention a center-to-center separation of the annular guide members of approximately 1½ to 2½ inches is sufficient to accomplish this function, the maximum distance of operation being determined by the coefficient of friction between the yarn and the annular guide surfaces and the relative diameters of the guide surfaces and the separator member such that the yarn does not contact the separator during delivery.

The axially and radially outer guide surface serves to artificially balloon the yarn and keep it away from substantial contact with a large portion of the yarn package, to prevent kinks in the yarn when withdrawal of yarn is stopped, by providing a surface for contact by the yarn to prevent slippage and spiralling of the yarn at this time, as well as generally maintaining the best tension control for the yarn during delivery, particularly in delivering or withdrawing low denier yarns (i.e. of the order of 7-20 denier), such as are employed particularly in the synthetic field as in knitting stockings, etc., such low denier yarns do not have enough mass to balloon sufficiently as a result of their rotational angular velocity to hold the yarn away from the package, and this normally causes considerable tension variation and kinks in the yarn due to varying contact of the delivered yarn with the yarn package per se. The large axially outer guide surface, which in the preferred application of the invention is a circular disc having a rounded peripheral edge, is thus employed in one of its functions to artificially balloon the yarn and keep it away from substantial contact with a large portion of the yarn package, particularly as used in the preferred application of the invention wherein yarn is withdrawn over the small end of a cone package.

It is another important aspect of the preferred application of the invention that the diameter of the large axially outer annular guide surface is related to the maximum diameter of the yarn package when half full and that the smaller axially inner annular guide surface is related in diameter to the diameter of the larger outer annular guide surface and the axial distance between the inner annular guide surface and the adjacent end of the yarn package per se, such that the most nearly uniform tension in the yarn is attained when delivery is being accomplished at the point when the yarn package is approximately one-half full, as compared to the full package as normally employed at the beginning of delivery therefrom. In the normal situation according to this aspect of the invention wherein the yarn is delivered from a barrel-build or double-taper-build package formed on a standard cone this results in the rubbing of the delivered yarn in transverse contact with a portion of the yarn package as the yarn is delivered from the area adjacent the lower end of the cone beneath the point of maximum diameter of the package. To completely prevent this rubbing would require a substantial increase in the diameter of the top or outer annular guide surface which would result in an undesirably large variation in the total wrap around angle of the yarn about the two guide surfaces as the yarn delivery point progressed from one end to the other of the yarn package. This would result in larger tension variations than are normally desired in fine denier yarn delivery, particularly for stocking knitting purposes, and such variation would be increasingly noticeable between the tensions occurring at the beginning of delivery when the package is substantially full and tensions occurring when the package is nearly empty, it being seen that the need for this much

larger diameter for the outer guide surface is no longer present when the yarn package is nearly empty. In other words, at the half-package point the relative ratios of the diameter of the two annular guide surfaces and the diameter of the yarn package at its maximum and minimum points when half delivered, with bottle or double-taper or similar builds, will be such that substantially the minimum tension variations occur as the point of delivery varies during withdrawal of the yarn from the package when approximately this size; whereas, when the yarn package is completely full this will result in there being a tension in the yarn as it is delivered from points in the area beneath the point of maximum diameter of the package which is greater than the tension in the yarn as it is delivered from the small end of the cone, but which is partially compensated by increased wrap around engagement with the two annular guide surfaces, the tension in the yarn when delivered from the point of maximum package diameter (near or at the bottom of the package) when the package is nearly empty will be smaller, if only slightly so, than the tension in the yarn as it is delivered from points adjacent or at the small end of the package.

Still other objects and attendant advantages will become apparent to one skilled in the art from a reading of the following detailed description of a preferred embodiment of the invention taken in conjunction with the accompanying drawings, wherein

Figure 1 illustrates in schematic side elevation a cone with a full package thereon in position for delivery of yarn therefrom according to the invention, with the general path of the yarn from various delivery points being indicated.

Figure 2 is a side elevation similar to Figure 1 when the package is approximately half exhausted, with the general path of the yarn from various delivery points being indicated.

Figure 3 is a further view similar to Figure 1 illustrating the delivery paths of the yarn from several points on the yarn package when the package is nearly exhausted.

Figure 4 is a perspective view illustrating the dual-flanged cap shown in Figures 1-3.

Referring now in detail to the figures of the drawings, a paper cone type bobbin 11, made of paper, composition, or other suitable material as may be desired, of standard 3°-51' taper mounted in upright position on a suitable support 13 as though the fitting of the open base of the cone 11 over a frusto-conical block 15 which may in turn be suitably secured against lateral movement on the support 13 as through the medium of a spike 16 secured to and extending upwardly from the support 13. The block 15 is complementary to the interior of the base or larger end of the cone 11 and thus holds the cone in substantially secure position against lateral or tilting movement thereof during delivery of yarn therefrom.

The invention is particularly adaptable to utilization with packages of yarn wound on a cone wherein the package is of the type having a double-taper or barrel-build, such double-taper or barrel-build package 17 being illustrated in the example shown in the drawings.

The yarn Y from the package 17 is withdrawn over the smaller end of the cone 11 and in engagement with a cap generally indicated at 19. The cap 19 has two different sized discs forming respectively a larger upper or axially outer rounded annular guide surface 21a and a relatively smaller inner rounded annular guide surface 23a, over and in engagement with which the yarn passes as it is delivered from the cone and package thereon. The discs or flanges 21 and 23 are suitably secured as by a press-fit or bonding or other desired manner to a cylindrical spacer tube 25 of suitable length, as for instance, approximately one inch in one physical embodiment as will be later set forth in more detail. The

cap 19 preferably has at the end 19b a tapered inferior end surface 19a of substantially complementary taper to that of the cone for purposes of stability in seating thereon, and is removably seated on the small end of the cone 11. Through the forming of the inside diameter of the spacer tube 25 at the end 19b thereof of a size corresponding to the diameter of the cone 11 at the desired seating position of the small guide surface end of the cap 19, the cap may be quickly and easily seated in proper position on the cone 11 without undue operator attention.

An axially aligned guide eye 27 is disposed at a suitable axial distance f from the larger guide member 21, the yarn thus proceeding from the package 17 over and into engagement with the annular guide surface 23a (depending upon the point of delivery of the yarn from the package 17) thence over the annular guide surface 21a, and through the axial guide eye 27, from which it may proceed to a knitting machine or other apparatus as may be desired.

Guide surface 23a is axially spaced apart an axial distance d from the yarn package 17 and this axial space d should be sufficiently large to prevent the wrap-around angle of the yarn on the rounded annular guide surface 23a from becoming too large and thus causing large tension changes and/or press-offs as the delivery point is at the adjacent end of the package, and also to prevent the yarn from being thrown up against the axially inner face of the disc 23. The distance d , however, should be sufficiently small, considering the coefficient of friction of the yarn and the guide surface 21a and 23a as well as the diameter of the smaller guide surface 23a and the adjacent end of the package 17, that the yarn does not engage the end of the cone during delivery movement between the package and the guide member 23, particularly since the end of the cone 11 is normally comparatively quite rough, and in any case such engagement would cause undesirable fluctuation in tension which, in many instances, would be of sufficient magnitude to cause breakage of the yarn. This distance d will vary somewhat with the variables noted above, including coefficient of friction and the various diameters of the elements, however, typical specific examples will be given hereinafter in order to fully exemplify this aspect of the practical invention to those skilled in the art.

As stated in the general description of the invention the distance e between the two guide surface members 21 and 23 should be sufficiently great that the guide surface 23a will be engaged by the yarn as it is delivered from the adjacent end of the package 17, while on the other hand, this distance e should be sufficiently small that the yarn will not wrap around the cylindrical member 25. For many practical applications of the invention, as are illustrated by specific dimensions from specific examples set forth hereinafter, a distance e of approximately one and one-half to two and one-half inches has been found quite satisfactory, although it will be apparent that with various specific size constructions of the various elements 21, 23, 11, etc., it may be necessary to vary this dimension beyond this range.

There is preferably disposed on the support 13 a ring 29 of light plush, cotton, felt, fur or the like about the base of the cone 11 in order to prevent entrapment of the yarn between the base end of the cone 11 and the support 13 in the event that loose yarn windings may be present on the package 17. Also, in order to prevent the possible snagging of yarn on possibly frayed edges of the base end of the bobbin, it is desirable to utilize a cone having its lower or base end 11a burnished, in accordance with usual practice in the construction of cones of this type. Further, in order to prevent the yarn from crushing the cone and forming a wrinkled peripheral surface which will interfere with smooth even withdrawal of the yarn, a cone is preferably utilized which is resin treated or the like, although it will be apparent that

such is not absolutely necessary to the practice of the invention. It will thus be appreciated that while a resin treated cone having a burnished lower or base end and a ring of light plush removably disposed and supported adjacent the lower or base end of the cone, is desirable and aids in the commercial practice of the invention, such are not actually necessary to the basic practice of the invention.

In a typical embodiment according to the invention as shown in Figure 1, the yarn is delivered from the full package 17 past and in engagement with the cap 19 and then through the axial guide eye 27. With this preferred illustrative embodiment when the point of delivery of the yarn Y from the package 17 lies approximately within the zone indicated at a , the yarn will rub in transverse contact with an axially adjacent portion of the yarn package and will then proceed through the artificial balloon path formed by its engagement with the annular surface 21a. It will be noted, however, that the wrap-around angle of the yarn about the rounded surface 21a will be quite small and at a minimum when the yarn is being delivered from this end zone a , as indicated schematically by the yarn paths Y_{a1} , Y_{a2} and Y_{a3} in Figures 1-3, respectively. When the yarn is delivered from approximately the zone b , as indicated schematically by yarn paths Y_{b1} , Y_{b2} and Y_{b3} , there will be substantially little or no rubbing contact between the delivered yarn and the axially adjacent windings of the package, due to the angle of delivery formed between the delivery point and the annular guide surface 21a relative to the taper angle of the package in this zone. When the yarn is being delivered from the zone indicated approximately at c , as indicated schematically by the yarn paths Y_{c1} , Y_{c2} and Y_{c3} , the yarn will contact both the outer and larger guide surface 21a and the inner and smaller guide surface 23a, the degree of wrap-around on the guide surface 23a varying inversely with the axial distance between the guide member 23 and the point of delivery in the zone c . It will be readily apparent that the effect of the delivery of the yarn over the guide surfaces 21a and 23a as described above will result in a substantial compensation of many of the various tension-variations which would occur through simple withdrawal of the yarn over the end of the package 17, and is highly superior to arrangements employing a single annular guide surface; two guide surfaces of equal size of two different sized guide surfaces with plush or the like disposed therebetween.

As the diameter of the package decreases during the delivery of the yarn, the zone c will normally be lengthened somewhat, with the transition point or zone 33 between the zones b and c moving toward the base of the cone to a position as approximately indicated at 33a. The approximate transition point or zone between the zones a and b , as indicated at 31, will also move toward the base, with the transition zone 31 being located as at 31a when the yarn package is substantially exhausted. It will be apparent that these points are not exact and that there is not actually an absolute unvarying transition point involved, but only a transition zone 31 between each of the zones a and b and a second transition zone 33 between the general zones b and c , these general zones a , b , and c and transitional zones 31 and 33 being indicated merely for the purpose of illustrating the approximate mode of operation according to a preferred aspect of the invention.

As stated further in the general description of the invention, the diameter of the axially outer annular guide surface 21a is related to the maximum diameter of the yarn package when half full, and the diameter of the smaller axially inner annular guide surface 23a is related to the diameter of the larger annular guide surface and the axial distance d between the inner guide surface and the adjacent end of the yarn package 17, such that most nearly uniform tension in the yarn is attained when de-

livery is being accomplished with the yarn package approximately half full, as compared to the full package as normally employed at the beginning of delivery therefrom. This is an important aspect in assuring the minimum variation of tension both from a standpoint of variation as the yarn delivery point traverses through the zones *a*, *b*, *c* and as the size of the yarn package varies from full, as shown in Figure 1, to substantially empty, as shown in Figure 3. The approximate relative size of the yarn package in one preferred embodiment at the half delivered or half full point is illustrated in Figure 2. While it may appear superficially that the yarn will not engage the radially and axially inner smaller guide surface *23a* at the lower end of the zone *c*, such normally actually occurs due to the lag angle of the yarn as it proceeds from its point of delivery over the guide surface *21a*. It will thus be seen that even though a two dimensional straight line lying in an axial plane and intersecting the outer edges of the guide surface *21a* and *23a* would appear to render the zone *c* quite short, the lag angle of the yarn as it is delivered (as schematically illustrated at Y_{c1} , Y_{c2} and Y_{c3}) will cause the yarn to engage both surfaces *21a* and *23a* over a substantially longer zone as indicated approximately at *c*.

In one preferred physical embodiment according to the invention wherein 15 denier monofilament type 66 duPont nylon is unwound from a barrel-build package 17 wound on a standard paper cone of 3°-51' taper, the package being 3 1/4" in diameter at the largest point and having a length of approximately 8 1/2", the following dimensions have been found highly satisfactory, and produce optimum results:

Diameter of top disc 21	inches	3 1/2
Thickness of top disc 21	do	9/32
Diameter of bottom disc 23	do	2 5/16
Thickness of bottom disc 23	do	3/32
Center-to-center distance <i>e</i> between discs	do	2
Distance <i>d</i>	do	1
Distance <i>f</i> to guide eye 27	do	8 1/2
Radius of curvature of round edges 21a and 23a	inches	3/64
Package weight when full	ounces	11
Inches		
Cone length		10 3/4
Base diameter of cone		2 7/8
Diameter of package 17 at small end		1 1/2
Diameter of package 17 at base end		2 3/4
Diameter of package 17 at point of maximum build when half delivered		3 50
Diameter of package 17 at point of maximum build (full package)		3.4

With this arrangement yarn delivery from the cone has been found to produce stockings of better than 90% first quality, with the average tension variation being approximately 1.4 grams.

The approximate desirable ratio ranges for the diameters of the large disc 21, small disc 23, package at maximum build diameter and diameter of the package at the smallest point adjacent the disc 23, have been found to be substantially as set forth below:

$$R_1 = \frac{\text{diameter of the larger disc 21}}{\text{diameter of the smaller disc 23}} = 1.4-1.6:1$$

$$R_2 = \frac{\text{diameter of the large disc 21}}{\text{package diameter at maximum build when half delivered or half full}} = 1.08-1.27:1$$

$$R_3 = \frac{\text{diameter of the small disc 23}}{\text{diameter of the package at the smallest point adjacent the disc 23}} = 1.3-1.6:1$$

The optimum ratios for a number of practical examples, as illustrated above, have been found to be $R_1=1.5$, $R_2=1.17$ and $R_3=1.3:1$.

While the invention has been illustrated as applied to a vertically disposed cone mounted for up-delivery, and such is greatly preferred, it will be apparent that such is not limited to this mounting disposition, it being feasible to employ the invention for down delivery or horizontal delivery as well, although such types of delivery have drawbacks which normally render them less desirable.

I claim:

1. The combination for supplying twisted synthetic yarn comprising a cone having a package of twisted synthetic yarn wound thereon in a substantially barrel-shaped build, a yarn guide arrangement disposed on the small end of said cone and comprising a pair of spaced apart substantially parallel discs and a cylindrical spacer sleeve therebetween, one of said discs having an aperture therein and being removably fitted over said small end of said cone, said one disc being smaller in diameter than the other of said discs and spaced from the smaller end of said yarn package, the ratio R_1 of the diameter of said other disc to the diameter of said one disc lying substantially in the range of 1.4-1.6:1, and the ratio R_2 of the diameter of said other disc to the maximum diameter of said package when one-half of its original linear length remains in said package lying substantially in the range of 1.08-1.27:1, the ratio R_3 of the diameter of said one disc to the diameter of the adjacent end of the full package being substantially in the range of 1.3-1.6:1, the tape of said cone being substantially in the range of 2-10°.

2. The combination according to claim 1 wherein R_1 is substantially 1.5:1, R_2 is substantially 1.17:1, and the ratio R_3 is substantially 1.3:1, and said cone is substantially 3°-51'.

3. The combination for supplying twisted synthetic yarn comprising a cone having a package of twisted synthetic yarn wound thereon in a substantially barrel-shaped build, a yarn guide arrangement disposed on the small end of said cone and comprising a pair of spaced apart substantially parallel discs and a cylindrical spacer sleeve therebetween, one of said discs having an aperture therein and being removably fitted over said small end of said cone, said one disc being smaller in diameter than the other of said discs and spaced from the smaller end of said yarn package, said spacer sleeve having a tapered inner surface adjacent the end thereof having said smaller disc thereon, said taper being complementary to the taper of said cone.

4. The combination for supplying twisted synthetic yarn comprising a cone having a package of twisted synthetic yarn wound thereon in a substantially barrel-shaped build, a yarn guide arrangement disposed on the small end of said cone and comprising a pair of spaced apart substantially parallel discs and a spacer member therebetween, one of said discs being smaller in diameter than the other of said discs and spaced from said yarn package, said one disc being closer to said package than said other disc, the ratio R_1 of the diameter of said other disc to the diameter of said one disc lying substantially in the range of 1.4-1.6:1, and the ratio R_2 of the diameter of said other disc to the maximum diameter of said package when one-half of its original linear length remains in said package lying substantially in the range of 1.08-1.27:1, the ratio R_3 of the diameter of said one disc to the diameter of the adjacent end of the full package being substantially in the range of 1.3-1.6:1.

5. The combination according to claim 4 wherein R_1 is substantially 1.5:1, R_2 is substantially 1.7:1, and the ratio R_3 is substantially 1.3:1.
